(57) CLAIM

The ornamental design for a jacket, as shown and described.

DESCRIPTION

FIG. 1 is a front, right side perspective view of a jacket showing my new design according to the first embodiment; FIG. 2 is a front elevation view thereof; FIG. 3 is a back elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a front, right side perspective view of a second embodiment of a jacket showing my new design; FIG. 9 is a front elevation view thereof; FIG. 10 is a back elevation view thereof; FIG. 11 is a right side elevation view thereof; FIG. 12 is a left side elevation view thereof; FIG. 13 is a top plan view thereof; and, FIG. 14 is a bottom plan view thereof.

In FIGS. 1-14, the thinner wider spaced broken lines on the jacket showing the collar, zipper pulls, inside of the jacket and any sleeves, form no part of the claimed design. The long dark dashed broken lines along the surfaces of the jacket depict claimed stitching.
